CLAIM

The ornamental design for a water pitcher, as shown and described.

DESCRIPTION

FIG. 1 is a perspective view of a water pitcher showing the new design;

FIG. 2 is a left side view thereof, the right side view being a mirror image of the left side view shown;

FIG. 3 is a front view thereof;

FIG. 4 is a back view thereof;

FIG. 5 is a top view thereof; and,

FIG. 6 is a bottom view thereof.
